DESIGN FOR AN ILLUMINATED PICTURE FRAME

Ernest G. Steinward, Portland, Oreg.

Application April 6, 1942, Serial No. 106,472

Term of patent 7 years

To all whom it may concern:

Be it known that I, Ernest G. Steinward, a subject of Germany, residing at 2037 Northwest Savier, in the county of Multnomah and State of Oregon, have invented a new, original, and ornamental Design for Illuminated Picture Frames, of which the following is a specification, reference being had to the accompanying drawing, forming part thereof.

Figure 1 is a front elevational view of an illuminated picture frame showing my new design; Figure 2 is a side elevational view; and Figure 3 is a top plan view.

I claim:

The ornamental design for an illuminated picture frame, as shown.

ERNEST G. STEINWARD.
